UNITED STATES PATENT OFFICE.

PRIESTLY MORRISON, OF NEW YORK, N. Y.

SUSPENSORY.

Application filed July 14, 1922. Serial No. 575,029.

My invention relates to suspension and supporting means for bodily use and, in particular, to means for supporting the scrotum.

The object of my invention is to produce a suspensor which is simple in construction, easily taken apart, the entire truss, as well as each part thereof, being washable, and having a stress distributing property which eliminates the many discomforts to which the wearer is usually subjected. Another object of my invention is to construct my suspensor in such a manner that the parts which are adjustable remain in their adjusted position.

Referring to the drawings, Figure 1 is a front view of my suspensor when the wearer thereof stands still. Figure 2 shows the same suspensor when the wearer assumes a different position or is in motion. Figures 3 and 4 are stress diagrams corresponding, respectively, to Figures 1 and 2. Figures 5 and 6 are variants of the girdle used in my invention. Figure 7 is a modification of my invention showing a different method of adjusting the length of the girdle and of the connection between the girdle and the scrotum sack. Figure 8 is another modification of the girdle construction and shows my preferred form in detail. Figure 9 is a variant of the sack used in connection with my invention.

Figures 1 and 2 are intended to show the general disposition of the suspension means and some of the details of my preferred form are not shown in order not to complicate the drawings. In these figures, the strap 1 is doubled on itself at the ends 2, 2', forming loops for the passage of the cord or lace 3, the ends 2, 2', being made fast to the strap 1 at 4, 4', which may be buttons attached to the strap and passing through corresponding button holes in the ends 2, 2', or snap fasteners. The scrotum sack 7 is connected with the strap 1 by means of the cord or lace 3. The cord 3 is attached to the sack 7 at the extreme points 8, 8', of its upper portion and passes through the loops formed by the ends 2, 2', with an easy sliding motion. It will be seen that the connection between the sack and the strap is uni-

filar. The length of this unifilar connection is shown as fixed in this form.

In Figures 3 and 4, the points 4, 4', 8, 8', of the diagrams correspond to the points bearing the same notation in Figures 1 and 2. The point 10 is obtained by intersecting the lines 4—8 and 4'—8'. While the diagrams formed by the points 4, 4', 8, 8', more nearly represent the construction of Figures 1 and 2, yet, for the purpose of examining the stresses in the suspensor, these diagrams may be replaced by those formed by the three points 4, 4' and 10. Then the force F represents the pull on the sack 7, while the forces F' and F'' represent the pull on the ends of the strap 1. The force F is directed vertically, while the forces F' and F'' are directed along the length of the strap 1 at each end respectively. The characteristics of the aforesaid diagram remain unchanged for different positions of the body, the three forces F, F', F'' always meeting at one point 11 and entirely balancing one another. The force F is due to the weight of the scrotum. This weight is relieved by the pull of the forces F', F'', or, rather, by the vertical components of these forces, while their horizontal components serve to keep the sack distended. This is made clear by the decomposition of forces at the points 8, 8', of the two diagrams, wherein f', f'', applied at the points 8, 8', are the vertical components of stress which act to support the scrotum, and f³, f⁴, are the horizontal components of stress which serve to keep the sack distended.

Figure 5 shows how the strap 1 may be made adjustable by the insertion therein of the elastic band 6. In this modification of the strap, I have provided it with button holes 4'', 4''', in both, the under and the upper parts of the loop formed by the ends 2, 2', so that a removable button or stud may be passed through corresponding button holes and thus close the loops. By adding a few more button holes at each end, the length of the strap may be adjusted in a suitable manner.

In Figure 6, the length of the strap 1 is made adjustable by means of the buckle 5' located about the middle of the strap.

In Figure 7, I have shown another method of fastening the looped ends of the strap 1, namely, by means of the buckles 5, 5'. The cord 3 does not form a continuous unit as it passes from one end of the sack to the other, through the looped ends of the strap, but is broken at one point and the broken ends are tied together in a knot 9. In this construction, adjustment of length is obtained for both, the strap, and the cord which connects the strap to the sack, thereby permitting the distance of the sack from the strap to be adjusted.

My preferred form differs from the preceding constructions in the details of the terminals of the strap. As stated above, these details were omitted from the Figures 1 and 2, for the sake of clearness. They are shown in Figure 8. In the preferred form of my invention, the loop 2" is independent of the strap 1 and is, preferably, sewed on to the protecting strip 12. The loop 2" is closed by means of the snap fastener 4. Through the loop 2" pass the sliding cord 3 and one end of the buckle 5", the strap 1 passing through the other end of the buckle 5" which is adapted to grip and hold the strap in place. The protecting strip 12 intervenes between the body of the wearer and the buckle 5" and snap 4.

Figure 9 shows a form of sack 7 having a band 7' on the back thereof, with eyelets 8", 8'", at the ends of the band 7', the eyelet holes being adapted to receive the cord 3 (not shown). By this arrangement, the cord 3 may be removably attached to the sack 7 at 8", 8'", instead of being broken and tied by a knot, as at 9 in the construction of Figure 7.

The strap 1 may be made of any suitable material, but, preferably, of webbing or flat tape. It will be seen that the sack is removable from the strap, so that any form of sack may be used and changes of sack may be made. All parts are washable, if proper material is used. The uni-filar member 3 is preferably made of soft, pliable lacing cord, solid or tubular, provided its surface and consistency are such as to facilitate its sliding motion. As it is adjustable in length, the sack will be adjustable as regards its position relatively to the strap and may be readily positioned exactly under the scrotum. Furthermore, it is clear that the uni-filar member will closely follow abdominal lines, and its easy adaptability as the body changes its position enables the stresses in the suspensory to preserve a state of equilibrium under all conditions. The pull from the weighted scrotum sack to the strap ends being always in the longitudinal direction of the strap, there is no tendency for the strap to slip or to be pulled down. On the other hand, the stress diagram shows that the scrotum sack is always subjected to

an upward vertical pull from the strap, and, by the combined adjustment of the strap and of the uni-filar member, this upward pull can be made exactly equal to the weight upon the scrotum sack, so that the latter is supported with the necessary amount of pull. Also, it will be seen from the diagram that the horizontal pull on the sack, at its extreme points, where it is attached to the uni-filar member, is so directed as to keep the sack distended.

An important feature of my invention, disclosed in the preferred form thereof, details of which are shown in Figure 8, resides in the ability of adjusting the strap 1 by means of the buckle 5", or any equivalent device, in such a manner that, after being adjusted in a position comfortable to the wearer, the buckle, or equivalent device, will remain in the adjusted position, even should it be necessary to shorten or lengthen the strap. Another feature of my preferred form is that the cord 3, in sliding through the looped member, rests against the snap fastener 4, which facilitates the sliding motion by reducing the sliding friction.

While I have shown and described, and pointed out in the annexed claims, certain novel features of my invention, various changes, omissions or substitutions in the form and details of the device as illustrated, and its operation, may be made by those skilled in the art, without departing from the spirit of my invention.

I claim:

1. A suspensory comprising a strap, terminals for said strap, each terminal comprising a looped member having two ends, a fastener for the ends of said looped member, a buckle removably connected to said looped member and adapted to grip one end of said strap, a pliable cord adapted to freely slide through the looped members of said terminals over said fasteners, a protecting strip under each one of said terminals, a scrotum sack, and means for adjustably and removably attaching said cord to said sack.

2. A strap adapted to be fitted over a portion of the lower trunk of a human body and having terminal loops, means for closing and opening said terminal loops, said means comprising friction reducing members, a scrotum sack, and a cord movably connecting said sack to said strap at said terminal loops and freely slidable over said friction reducing members.

3. In a suspensory, the combination with a scrotum sack, of a strap adapted to girdle a portion of said body and having removable terminals, rigid friction reducing members within said terminals, and a connecting member between said scrotum sack and said strap adapted to freely slide over said rigid friction reducing members.

4. The combination with a girdle, of a

member adapted to be subject to pull, and means for transmitting said pull from said member to said girdle, comprising snap fasteners on said girdle and a connecting member adapted to slide through said girdle over said snap fasteners.

5. The combination with a strap, of ter-

minals therefor, a loop for each terminal, a snap fastener for each loop, a pendulous member and a connecting member between said pendulous member and said strap adapted to slide through said loops over the shanks of said snap fasteners.

10 PRIESTLY MORRISON.
